CIRCUIT BREAKER MECHANISM

Fritz E. Florschutz and Carl G. Lentjes, Pittsburgh, Pa., assignors to Westinghouse Electric Corporation, East Pittsburgh, Pa., a corporation of Pennsylvania

Application August 5, 1950, Serial No. 177,816

15 Claims. (Cl. 200—82)

1

This invention relates to circuit breakers and more particularly to circuit breaker operating mechanisms of the pneumatic type.

An object of the invention is to provide an improved fluid pressure operated circuit breaker operating mechanism which is mechanically trip free and capable of effecting high-speed opening and reclosing of the circuit breaker.

Another object of the invention is to provide a circuit breaker operating mechanism operable by fluid pressure in which the breaker is releasably connected to the operating mechanism by means of an improved high-speed, light-load latching mechanism.

Another object of the invention is to provide an improved circuit breaker having a fluid motor operating mechanism including a releasable coupling providing a trip-free connection between the motor and the breaker which permits high-speed reconnection of the operating mechanism to the circuit breaker before the breaker reaches full open position.

Another object of the invention is to provide a circuit breaker with an improved operating mechanism of the pneumatic type capable of effecting high-speed operation of the circuit breaker and operating piston and quick reversal of the moving parts.

Another object of the invention is to provide a circuit breaker with an improved operating mechanism of the pneumatic type capable of effecting high-speed opening and quick reclosing of the circuit breaker.

Another object of the invention is to provide an improved circuit breaker operating mechanism of the compressed fluid operated type, which is simple, reliable in operation and inexpensive to manufacture.

The novel features that are considered characteristic of the invention are set forth in particular in the appended claims. The invention itself, however, both as to structure and operation, together with additional objects and advantages thereof, will be best understood from the following detailed description of a single embodiment thereof when read in conjunction with the accompanying drawings.

In said drawings:

Figure 1 is a side elevational view of a circuit breaker operating mechanism embodying the principles of the invention;

Fig. 2 is a vertical sectional view taken substantially on line II—II of Fig. 1 and looking in the direction indicated by the arrows;

Fig. 3 is a fragmentary elevational view of the

2

latching mechanism and the trip-free mechanism with the parts in the tripped position but before the breaker has moved to the full open position;

Fig. 4 is a view similar to Fig. 3 showing the parts in their reconnected and relatched positions;

Fig. 5 is an enlarged sectional view, taken on line V—V of Fig. 1 showing the valve mechanism for controlling the admission of compressed fluid to the operating motor.

Fig. 6 is a fragmentary view showing a modification of the trip-free mechanism.

Referring to Fig. 2 of the drawing, the circuit breaker 11 which is illustrated diagrammatically, may be of any conventional construction either oil-break, air-break or gas-blast type and is adapted to be operated to the open position by means of an accelerating spring 13. The circuit breaker is adapted to be operated to the closed position by means of an operating mechanism which in the embodiment shown is of the compressed fluid type. The operating mechanism includes a main casting 15 (Figs. 1 and 2) formed to provide an operating cylinder 17 closed at its upper end by a plate 19 secured to the casting 15 by means of bolts 21 (Fig. 1). Mounted in the operating cylinder 17 (Fig. 2) is an operating piston 23 having secured thereto a piston rod 25 which is slidable through an air-tight opening in the plate 19. Rigidly secured to the upper end of the piston rod 25 is a coupling 27 which is releasably connected to a coupling 29 rigidly secured to a breaker operating rod 31 by means of an inverted or overlapping toggle comprising toggle links 33 and 35. The breaker operating rod 31 is operatively connected to the circuit breaker 11 by means of a suitable linkage.

The toggle link 33 comprises a pair of spaced parallel links pivotally connected by means of a pivot pin 37 to the coupling 27. The toggle link 35 comprises a single link disposed between the links 33 and is pivotally connected by means of a pivot pin 39 to the coupling 29. The toggle links 33 and 35 are pivotally connected together by 45 means of a knee pivot pin 41.

In order to provide for straight-line movement of the piston rod 25 and the breaker operating rod 31, and to assist the trip-free toggle 33—35 in maintaining the breaker closed, each of the pivot pins 37 and 39 are provided with rollers 43, there being a roller 43 mounted on each end of each of the pivot pins 37 and 39. These rollers cooperate with corresponding vertical slots 45 formed in a pair of spaced frame members 47 rigidly mounted on the plate 19 and extending

upwardly therefrom in spaced parallel relation. In order to provide suitable bearing surfaces for the rollers 43, plates 49 provided with slots coinciding with the slots 45 are secured to the outside of each of the frame members 47 in any suitable manner, preferably by welding.

The circuit breaker is held in the closed position by means of a main latch 51 and a light load latch mechanism indicated generally at 53. The main latch 51 is pivotally mounted on a pin 55 supported in the frame members 47 and is biased by means of a spring pressed plunger 57 into latching engagement with a latching surface 59 on the coupling 27. The plunger 57 is slidably mounted in an opening in a cross bar 61 rigidly supported between the frames 47 and is biased by means of a compression spring 63 compressed between the cross bar 61 and a washer 65 on the plunger. The main latch 51 is provided with a latching surface 67 for cooperating with the latching surface 59 on the coupling 27 and also has a downwardly extending projection 69 the purpose of which will be described later.

The light-load latching mechanism 53 includes an under-set tripping toggle comprising toggle links 71 and 73 and a trigger latch 75 cooperating to releasably maintain the tripping toggle in its underset position. The toggle link 71 comprises a pair of links rigidly joined by a cross member 77 and are pivotally mounted on a fixed pivot pin 79 supported by the frame members 47. At their free ends the toggle links 71 carry between them a latch roller 81 with which the trigger latch 75 cooperates to maintain the tripping toggle 71-73 in its underset position. The toggle link 73 comprises a pair of spaced parallel links disposed one on each side of the link 71 and pivoted on the knee pivot pin 41 of the trip free toggle 33-35 outside of the toggle links 33. The toggle links 73 are pivotally connected to the toggle link 71 by means of a knee pivot pin 83.

The trigger latch 75 is pivotally mounted on a pivot pin 85 supported in a pair of spaced brackets 87 (only one being shown) which in turn are rigidly secured to a cross plate 89 mounted on the under side of the cross plate 89 is a tripping electromagnet 91 comprising a fixed magnet yoke 93, an energizing winding 95 and a movable armature 97. A trip rod 99 is secured to the armature 97 and extends upwardly through an opening in the magnet and through an opening in the plate 89, the upper end of the rod 99 being disposed beneath a projection 101 of the trigger latch 75.

A spring 103 biases the latch 75 to latching position which is determined by a cross bar 105 between the side members of the toggle link 71 adjacent the latch roller. The underset position of the tripping toggles 71-73 is adjustably determined by means of an adjustable stop screw 107 threadedly engaging a cross bar 109 rigidly supported between the frames 47 and locked in adjusted position by a lock nut 111.

A latch checking switch 113 is provided for checking the position of the trigger latch 75. The switch 113 is mounted on one of the frames 47 and the contacts (not shown) are controlled by a plunger 115 which is engaged by an adjustable stud 117 mounted in an arm 119 integral with the latch 75 when the latch is in latching position.

Assuming the breaker to be in the closed position it is tripped open in the following manner:

Referring to Fig. 2 of the drawings, in the closed position of the breaker the main latch

51 holds the piston 23 in the closed position in which it is shown against the force of nested compression springs 121 compressed between the bottom of the piston 25 and the bottom of a downwardly extending cylindrical portion 133 of the main casting 15. The accelerating spring 13 applies an upward force on the breaker operating rod. Since the pivot pins 31 and 39 are constrained by the slots 45 to move in a straight line, a small component of this force is applied through the link 35 to the tripping toggle 71-73. Due to the tripping toggle being only slightly underset a very small component of the force of the accelerating spring is applied through the tripping toggle 71-73 and the latch roller 81 to the light-load latch 75.

When the tripping electromagnet 91 is energized from a suitable source the armature 97 moves the trip rod 99 upward to engage and actuate the trigger latch 75 in unlatching direction to release the underset tripping toggle 71-73. The force of the accelerating spring 13 applied to the tripping toggle immediately causes this toggle to collapse to the position shown in Fig. 3. As soon as the tripping toggle 71-73 starts to collapse the breaker operating rod 31 starts to move upwardly to open the breaker. The upward movement of the breaker operating rod 31 and the collapse of the tripping toggle 71-73 causes clockwise rotation of the trip-free toggle link 33. When the breaker rod 31 has traveled upwardly a very short distance, approximately one-half inch, a tail 125 on the toggle link 33 below the pivot pin 37 engages the projection 69 on the main latch 51 and cams the main latch 51 to unlatching position and releases the piston rod 23, whereupon the powerful springs 121 thrusts the piston 23 and the piston rod 25 upwardly at a speed greater than the opening speed of the breaker operating rod 31. Since the pivot pins 37 and 39 are constrained by the slot 45 to travel in a straight line and the speed of upward movement of the pin 37 is greater than the speed of the pin 39, the toggle link 33 will cause the link 35 to rotate counterclockwise about the pivot 39 toward the normal inverted position of the toggle 33-35. This action through the pin 41 and link 73 rotates the link 71 clockwise about its pivot 79 far enough to permit reengagement of the trigger latch 75 under the latch roller 81. This effectively recouples the piston rod 25 to the breaker operating rod 31 and the parts thereafter travel in unison to the full open position of the breaker moving the piston 23 to the top of the cylinder 17.

Recoupling of the piston rod 25 to the breaker operating rod 31 may be effected earlier in the opening operation by using the modification illustrated in Fig. 6 of the drawings. In this modification the piston rod 25 is connected to the breaker operating rod 31 by means of an inverted toggle comprising toggle links 33a and 35a respectively pivoted on the pivot pins 37 and 39. The toggle links 33a and 35a are pivotally connected together and to the tripping toggle 71-73 by the knee pin 41. The tail 125 is omitted from the toggle link 33a, and the toggle link 35a is provided with a tail 125a. Also the projection 69 is omitted from the latch 51a.

The operation of the trip-free toggle shown in Fig. 6 is the same as that shown in Figs. 2, 3, and 4 with the exception that the main holding latch 51a is actuated to unlatching position by the toggle link 35a instead of the lower toggle link 33a. The speed of angular movement of the toggle link

35a about its pivot 39 is approximately twice that of the toggle link 33a about its pivot 37. Also, the tail 125a actuates the latch 51a with a much smaller lever-arm than the tail 125 (Fig. 1). The combination of these features effects unlatching of the piston rod after a movement of only approximately $\frac{1}{2}$ of an inch travel of the breaker rod in opening direction following a tripping operation. This results in quicker recoupling of the piston rod to the breaker rod.

The circuit breaker is closed by admitting compressed gas to the operating cylinder above the piston 23. The trip-free toggle 33-35 and the latch mechanism is shown in Fig. 4 in the fully open position of the breaker. When compressed gas is admitted to the cylinder 17 the piston 23 and the piston rod 25 are forced downwardly drawing the link 33 therewith. Since the toggle link 71 of the tripping toggle is now latched in the position shown in Fig. 4, the link 73 pivots about its pivot pin 83, which acts as a fixed pivot, thereby holding the toggle 33-35 in thrust transmitting position during the closing operation. The closing force applied to the link 33 is, therefore, transmitted through the link 35 to move the breaker operating rod downwardly and close the breaker.

Compressed gas is admitted to the cylinder 17 to close the circuit breaker by means of an inlet valve device indicated generally at 126 (Figs. 1 and 5). The inlet valve device comprises a main housing 127 secured to the top of the plate 19, which closes the upper end of the operating cylinder 17, by means of bolts 129 (only one being shown). The housing 127 has a cylinder 131 formed therein in which is disposed a valve-operating piston 133. Rigidly secured to the piston 133 is a valve rod 135 extending downwardly through a guide bearing 137, and a valve member 139 is secured to the lower end of the valve rod 135 by means of a nut 141. The valve member 139 is provided with a valve facing 143 composed of a tough, resilient material and is normally seated against an annular valve seat 145 formed in the housing 127 around a large inlet passage 147. The cylinder 131 is closed at its upper end by means of a closure member 149 threadedly engaging an enlarged opening in the housing 127.

The valve 139 and the piston 133 are biased to the closed position by means of a spring 151 compressed between the valve member 139 and a closure plate 153 suitably secured to the bottom of the housing 127 by means of bolts 155. A high-pressure chamber 157 in the housing 127 below the valve 139 is supplied with fluid under pressure from a suitable source by means of a passage 159. An inlet port 161 (Fig. 5) above the valve 139 communicates with the operating cylinder 17 (Fig. 2) by means of a passage formed by a portion 163 (Fig. 1) of the housing 127.

The inlet valve 139 is operated to the open position by admitting fluid under pressure from the high-pressure chamber 157 to the cylinder 131 above the valve-operating piston 133. This is accomplished by means of an electromagnetically operated pilot valve device indicated generally at 165 (Fig. 5). The pilot valve device comprises a housing 167 secured to the housing 127 of the inlet valve device by means of bolts 169 (only one being shown). The housing 167 is provided with a chamber 171 communicating by means of a passage 173 with the high-pressure chamber 157. A valve 175 normally closes off the chamber 171 from a passage 177 communicating with the cylinder 131 above the piston 133. The valve 175 is biased

to closed position by means of a spring 179 and is secured on a rod 181 which, in turn, is attached to the armature (not shown) of an electromagnet 183. Also mounted on the rod 181 is an exhaust valve 185 normally opening the passage 177 to atmosphere and which closes this passage upon opening of the valve 175 to admit compressed fluid to operate the piston 133.

Formed in the housing 127 is a cylinder 187 in which is disposed a cup-shaped exhaust valve 189 for controlling a large exhaust port 191. The valve 189 has a reduced portion 193 disposed in a cylinder 195 which is communicated by means of a passage 197 with the cylinder 131 and the passage 177. The cylinder 187 above the valve 189 is normally at atmospheric pressure by virtue of one or more openings 199 therein.

The exhaust valve 189 is normally biased by means of gravity or suitable spring means (not shown) to the closed position where it is seated on a beveled annular valve seat 201 which is screwed into the housing 127. A chamber 203 surrounding the valve seat 201 and the lower portion of the valve 189 is communicated with the inlet port 161 by means of a large passage 205.

When the electromagnet 183 is energized (from a suitable source not shown) the rod 181 is moved downwardly closing the exhaust valve 185 and opening the valve 175 thus admitting fluid under pressure from the high-pressure chamber 157 through the passages 173 and 177 to the cylinder 131 above the piston 133. This forces the piston 133 down moving the valve member 139 to open position to admit compressed fluid through the passage 167 and the inlet port 161 to the operating cylinder 17 to close the breaker in the previously described manner.

At the same time compressed fluid is admitted to the cylinder 131 to effect opening of the inlet valve 139, compressed fluid is also admitted through the passage 197 to the cylinder 195 above the portion 193 of the exhaust valve 189 to maintain the exhaust valve closed during the circuit breaker closing operation.

When the electromagnet 183 is deenergized near the end of a closing operation, the valve 175 closes and the valve 185 opens to vent the high-pressure fluid from the cylinder 131 to permit the spring 151 to close the inlet valve 139. At the same time, the high-pressure fluid is vented from the cylinder 195 through the passages 197 and 177 whereupon the closing charge of high-pressure fluid in the operating cylinder 17 and in the chamber 203 blasts the exhaust valve 189 to open position to vent the compressed fluid from the operating cylinder 17. As soon as the closing charge of compressed fluid is exhausted from the operating cylinder, the exhaust valve is restored by the force of gravity or other biasing means (not shown) to its closed position.

When the breaker arrives at the fully closed position the spring 63 (Fig. 2) moves the latch 51 into engagement with the coupling to hold the mechanism and the breaker in the closed position.

If there is no fault condition such as an overload or short circuit in the main circuit at the time the contacts are closed, the circuit breaker will be latched closed as just described. However, if there is a fault condition on the main circuit at the time the circuit breaker completes the main circuit the trip device 91 will be immediately energized and effect release of the latching mechanism 53 to trip the breaker free of the operating piston 23.

The operating mechanism is operable to effect

normal closing operation of the circuit breaker and also instantaneous automatic reclosing operation of the circuit breaker, by means of a suitable control circuit (not shown) of conventional type for energizing the electromagnet 183 of the inlet valve device 126. The control circuit for controlling the energization of the inlet valve electromagnet and the tripping electromagnet 91 may be similar to the control circuit disclosed in Patent No. 2,408,199, issued September 24, 1946, to James M. Cumming and Richard C. Cunningham and assigned to the assignee of the present invention.

If the control circuit is set for instantaneous automatic reclosing, the electromagnet 183 of the inlet valve device will be energized by means of the latch checking switch 113 the instant the trigger latch 75 (Fig. 2) reaches latched position. This occurs at approximately the time in the opening stroke when the breaker contacts have separated far enough to extinguish the arc. As set forth previously, relatching of the trigger latch 75 effectively recouples the piston rod 25 to the breaker operating rod. Energization of the electromagnet 183 effects opening of the main inlet valve 139 and admits compressed gas to the cylinder 17 to effect closing of the breaker.

While the invention has been disclosed in accordance with the provisions of the patent statutes, it is to be understood that various changes in structural details thereof may be made without departing from the spirit of the invention.

We claim as our invention:

1. A high-speed operating mechanism for a circuit breaker comprising a cylinder, a piston in said cylinder operable to close said breaker, a piston rod attached to said piston and extending outside said cylinder, a breaker operating rod disposed in axial alignment with said piston, an inverted toggle connecting said piston rod and said operating rod, means constraining the ends of said inverted toggle for movement in a straight line, a tripping toggle connected to the knee of said inverted toggle for normally restraining the said inverted toggle in thrust transmitting position, a trigger latch normally restraining said tripping toggle in restraining position, trip means responsive to abnormal circuit conditions to actuate said trigger latch to release said tripping toggle and effect opening movement of said breaker rod free of said piston, and spring means for effecting high-speed movement of said piston to relatch said tripping toggle and restore said inverted toggle to thrust transmitting position at least by the time said breaker reaches open position.

2. A high-speed operating mechanism for a circuit breaker comprising a cylinder, a piston in said cylinder operable to close said breaker, a piston rod attached to said piston and extending outside said cylinder, a breaker operating rod disposed in axial alignment with said piston, means constraining said piston rod and said breaker rod for movement in a straight line, an inverted toggle connecting said piston rod and said operating rod, a tripping toggle connected to said inverted toggle for normally restraining the latter in thrust transmitting position, a trigger latch normally restraining said tripping toggle in restraining position, trip means responsive to abnormal circuit conditions to actuate said trigger latch to release said tripping toggle and effect opening movement of said breaker rod free of said piston, and spring means for effecting high-speed movement of said piston to relatch said tripping toggle

and restore said inverted toggle to thrust transmitting condition at least by the time said breaker reaches open position.

3. A high-speed operating mechanism for a circuit breaker comprising a cylinder, a piston in said cylinder operable to close said breaker, a piston rod attached to said piston and extending outside said cylinder, a breaker operating rod disposed in axial alignment with said piston, a main latch releasably engaging said piston rod to normally restrain said piston and said breaker in closed position, an inverted toggle connecting said piston rod and said operating rod, a tripping toggle connected to said inverted toggle for normally restraining the latter in thrust transmitting position, a trigger latch normally restraining said tripping toggle in restraining position, trip means responsive to abnormal circuit conditions to actuate said trigger latch to release said tripping toggle and effect opening movement of said breaker rod free of said piston, spring means biasing said breaker open and operable upon release of said tripping toggle to move said breaker to open position, means on said inverted toggle for engaging and actuating said main latch upon initial opening movement of said breaker to effect release of said piston, and spring means for effecting high-speed movement of said piston to relatch said tripping toggle and return said inverted toggle to thrust transmitting position at least by the time said breaker reaches open position.

4. In an electrical circuit breaker having movable contact means, operating means for said breaker comprising spring means biasing said breaker to open position, an operating cylinder, an operating piston in said cylinder, means comprising an inverted toggle connecting said piston to said breaker, means constraining the ends of said inverted toggle for movement in a straight line, a tripping toggle normally restraining said inverted toggle in thrust transmitting position to hold said breaker in closed position, latch means releasably restraining said piston in closed position, trip means responsive to abnormal circuit conditions for causing said tripping toggle to release said inverted toggle and permit said spring means to open said breaker, a projection on said inverted toggle for engaging and actuating said latch means to release said piston during the first part of the opening movement of said breaker, and other spring means for moving said piston at a speed greater than the speed of opening movement of said breaker to effect high-speed resetting of said tripping toggle and resetting of said inverted toggle to thrust transmitting position.

5. In an electrical circuit breaker having movable contact means, operating means for said breaker comprising spring means biasing said breaker to open position, an operating cylinder, an operating piston in said cylinder, means comprising an inverted toggle connecting said piston to said breaker, means constraining the ends of said inverted toggle for movement in a straight line, a tripping toggle normally restraining said inverted toggle in thrust transmitting position to hold said breaker in closed position, latch means releasably restraining said piston in closed position, trip means responsive to abnormal circuit conditions for causing said tripping toggle to release said inverted toggle and permit said spring means to open said breaker, a projection on said inverted toggle for engaging and actuating said

latch means to release said piston during the first part of the opening movement of said breaker, and other spring means for moving said piston at a speed greater than the speed of opening movement of said breaker to effect high-speed resetting of said tripping toggle and resetting of said inverted toggle to thrust transmitting position, and valve means operable to admit compressed gas to said cylinder to effect high-speed reclosure of said breaker.

6. A high-speed operating mechanism for a circuit breaker comprising an operating cylinder, a piston movable therein to close said breaker, a piston rod attached to said piston and extending outside of said cylinder, a breaker operating rod disposed in axial alignment with said piston rod operable to close said breaker, means connecting said piston rod and said breaker operating rod comprising an inverted toggle having one end pivotally connected to said piston rod and the other end pivotally connected to said breaker operating rod, means constraining the ends of said toggle for movement in a straight line, a tripping toggle having one end pivotally connected to the knee of said inverted toggle and the other end pivoted on a fixed pivot, a light-load latch releasably restraining said tripping toggle in thrust transmitting position to restrain said inverted toggle in holding position, trip means for actuating said light-load latch to effect collapse of said tripping toggle and opening movement of said breaker rod free of said piston rod, spring means biasing said breaker open and operable upon collapse of said tripping toggle to move said breaker to open position, separate latch means normally restraining said piston rod against movement in opening direction, means on said inverted toggle operable at the beginning of the opening movement of said breaker rod to engage and actuate said separate latch means to release said piston rod, and resilient means for thereafter moving said piston and said piston rod at high speed to effect resetting of said tripping toggle and resetting of said inverted toggle to thrust transmitting position at least by the time the breaker reaches open position.

7. A high-speed operating mechanism for a circuit breaker comprising an operating cylinder, a piston movable therein to close said breaker, a piston rod attached to said piston and extending outside of said cylinder, a breaker operating rod disposed in axial alignment with said piston rod operable to close said breaker, means connecting said piston rod and said breaker operating rod comprising an inverted toggle having one end pivotally connected to said piston rod and the other end pivotally connected to said breaker operating rod, means constraining the ends of said toggle for movement in a straight line, a tripping toggle having one end pivotally connected to the knee of said inverted toggle and the other end pivoted on a fixed pivot, a light-load latch releasably restraining said tripping toggle in thrust transmitting position to restrain said inverted toggle in holding position, trip means for actuating said light-load latch to effect collapse of said tripping toggle and opening movement of said breaker rod free of said piston rod, spring means biasing said breaker open and operable upon collapse of said tripping toggle to move said breaker to open position, separate latch means normally restraining said piston rod against movement in opening direction, means on said inverted toggle operable at the beginning of the opening movement of said

breaker rod to engage and actuate said separate latch means to release said piston rod, resilient means for thereafter moving said piston and said piston rod at high speed to effect resetting of said tripping toggle and resetting of said inverted toggle to thrust transmitting position at least by the time the breaker reaches open position, and inlet valve means operable before said breaker reaches full open position to admit compressed gas to said cylinder to effect quick reversal of said mechanism and reclosure of said breaker.

8. A high-speed operating mechanism for a circuit breaker comprising power operated means for closing said breaker, connecting means comprising an inverted toggle connecting said power operated means to said circuit breaker, means restraining the ends of said inverted toggle for movement in a straight line, a tripping toggle connected to said inverted toggle for normally restraining the latter in thrust transmitting position, a trigger latch normally restraining said tripping toggle in restraining position, trip means responsive to abnormal circuit conditions to actuate said trigger latch to release said tripping toggle and effect opening of said breaker free of said power operated means, and spring means for moving said power operated means to effect high-speed relatching of said tripping toggle and resetting of said inverted toggle to thrust transmitting position at least by the time the breaker reaches full open position.

9. A high-speed operating mechanism for a circuit breaker comprising power operated means for closing said breaker, means releasably connecting said power operated means to said breaker comprising an inverted toggle having one end connected to said power operated means and the other end connected to said breaker, means restraining the ends of said inverted toggle for movement in a straight line, a tripping toggle connected to said inverted toggle normally restraining the latter in thrust transmitting position, a light-load latch releasably restraining said tripping toggle in restraining position, trip means for actuating said light-load latch to effect collapse of said tripping toggle and opening movement of said circuit breaker free of said power operated means, spring means biasing said breaker open and operable upon collapse of said tripping toggle to move said breaker to open position, separate latch means normally restraining said power operated means against movement in opening direction, means on said inverted toggle engaging said separate latch at the beginning of the opening movement of said breaker to actuate said separate latch to release said power operated means, and resilient means for thereafter moving said power operated means to effect high-speed resetting of said tripping toggle and resetting of said inverted toggle to thrust transmitting position.

10. A high-speed operating mechanism for a circuit breaker comprising a cylinder, a piston in said cylinder operable to close said breaker, a piston rod attached to said piston, latch means engaging said piston rod for releasably restraining said piston in closed position, a breaker operating rod disposed in axial alignment with said piston rod, means constraining said piston rod and said breaker rod for movement in a straight line, a main toggle connected to said breaker rod and said piston rod, one link of said toggle in the thrust-transmitting position of said toggle being in compression and the other link being in

tension, a tripping toggle connected to said main toggle for normally restraining the latter in thrust-transmitting position, trip means normally restraining said tripping toggle in restraining position and operable in response to abnormal circuit conditions to release said tripping toggle to effect opening movement of said breaker rod free of said piston rod, a spring biasing said breaker open and operable upon release of said tripping toggle to move said breaker to open position, one of said main toggle links actuating said latch means to release said piston, and spring means for effecting high-speed movement of said piston and piston rod in opening direction to reset said tripping toggle and restore said main toggle to thrust-transmitting position.

11. A high-speed operating mechanism for a circuit breaker having power-operated means for closing said breaker, connecting means comprising a pair of links pivotally connected together, one of said links being pivotally connected to said breaker and the other of said links being connected to said power-operated means, means constraining the points of connection of said links to said breaker and said power-operated means for movement in a straight line, trip means releasably holding said pair of links in thrust-transmitting position, one of said links in said thrust-transmitting positions being in compression and the other of said links being in tension, said trip means being operable in response to abnormal circuit conditions to release said links and effect opening movement of said breaker free of said power-operated means, spring means biasing said breaker open and operable upon release of said links to move said breaker to open position, and spring means for moving said power-operated means to effect high-speed resetting of said trip means and resetting of said pair of links to thrust-transmitting position at least by the time the breaker reaches full open position.

12. A high-speed operating mechanism for a circuit breaker comprising a cylinder, a piston in said cylinder operable to close said breaker, a piston rod attached to said piston, a latch biased to latching position in which it engages said piston rod to releasably restrain said piston in closed position, a breaker operating rod, a toggle comprising a pair of toggle links pivotally connected together, one end of said toggle being pivotally connected to said breaker rod and the other end of said toggle being connected to said piston rod, means constraining the ends of said toggle for movement in a straight line, trip means releasably restraining said toggle in thrust-transmitting position and operable in response to abnormal circuit conditions to release said toggle, one of said toggle links being in compression and the other in tension in the thrust-transmitting position of said toggle, said toggle links upon release of said toggle moving in the same direction to permit opening movement of said breaker free of said piston, spring means biasing said breaker open and operable upon release of said toggle to move said breaker to open position, means on one of said toggle links for engaging said latch when said toggle is released to effect release of said piston, and spring means for moving said piston and said piston rod to effect resetting of said toggle to thrust-transmitting position.

13. A high-speed operating mechanism for a circuit breaker comprising a cylinder, a piston in said cylinder operable to close said breaker, a

piston rod attached to said piston, latch means engaging said piston rod to releasably restrain said piston in closed position, a breaker-operating rod disposed in axial alignment with said piston rod, a main toggle comprising a pair of toggle links pivotally connected together, pivot means pivotally connecting one end of said toggle to said breaker-operating rod and the other end of said toggle to said piston rod, means guiding said pivot means for movement in a straight line, a tripping toggle connected to said main toggle for normally restraining said main toggle in thrust-transmitting position, one link of said main toggle being in compression and the other link being in tension in the thrust-transmitting position of said main toggle, trip means normally restraining said tripping toggle in restraining position and operable in response to abnormal circuit conditions to release said tripping toggle to effect opening movement of said breaker rod free of said piston, spring means biasing said breaker open and operable upon release of said tripping toggle to move said breaker to open position, one of said main toggle links upon release of said main toggle engaging and actuating said latch to release said piston, and spring means for actuating said piston to effect high-speed resetting of said tripping toggle and resetting of said main toggle to thrust-transmitting position.

14. A high-speed operating mechanism for a circuit breaker comprising power-operated means for closing said breaker, a main toggle comprising a pair of toggle links pivotally connected together, pivot means pivotally connecting one end of said toggle to said breaker and the other end of said toggle to said power-operated means, guide means cooperating with said pivot means to constrain said pivot means for movement in a straight line, a tripping toggle connected to said main toggle for normally restraining said main toggle in thrust-transmitting position, one link of said main toggle being in compression and the other link of said main toggle being in tension when said main toggle is in thrust-transmitting position, trip means normally restraining said tripping toggle in restraining position and operable in response to abnormal circuit conditions to release said tripping toggle to effect opening movement of said breaker free of said power-operated means, spring means biasing said breaker open and operable upon release of said tripping toggle to move said breaker to open position, and means for moving said power-operated means in opening direction to reset said tripping toggle to restraining position and to reset said main toggle to thrust-transmitting position at least by the time the breaker reaches full open position.

15. A high speed operating mechanism for a circuit breaker comprising a cylinder, a piston in said cylinder operable to close said breaker, a piston rod attached to said piston, a pivoted latch, biasing means biasing said latch to latching position in which said latch engages said piston rod and releasably restrains said piston in closed position, a breaker-operating rod disposed in axial alignment with said piston rod, a main toggle comprising a pair of toggle links pivotally connected together, pivot means pivotally connecting one end of said toggle to said breaker operating rod and the other end of said toggle to said piston rod, means guiding said pivot means for movement in a straight line, a tripping toggle connected to said main toggle for normally re-

straining said main toggle in thrust-transmitting position, one of said main toggle links being in compression and the other of said main toggle links being in tension in the thrust-transmitting position of said main toggle, trip means normally restraining said tripping toggle in restraining position and operable in response to abnormal circuit conditions to release said tripping toggle to effect opening movement of said breaker free of said piston, spring means biasing said breaker open and operable upon release of said tripping toggle to move said breaker to open position, one of said main toggle links upon release of said main toggle engaging and moving said latch to unlatching position to release said piston, spring means for moving said piston and piston rod in

opening direction to effect high-speed resetting of said tripping toggle and resetting of said main toggle to thrust-transmitting position, and said biasing means moving said latch into latching engagement with said piston rod when said breaker is moved to closed position.
